CIRCUIT ARRANGEMENT FOR THE TRANSMISSION OF SIGNALS

Friedrich Buckholtz, Stuttgart-Zuffenhausen, Germany, assignor to International Standard Electric Corporation, New York, N. Y., a corporation of Delaware

Application September 21, 1954, Serial No. 457,516

Claims priority, application Germany September 25, 1953

4 Claims. (Cl. 179—171)

It is often necessary in communications transmission systems to transmit signals from different sources independently of each other to a common transmission path. Consequently it is demanded that the individual signals have to be transferred in a decoupled manner to the common transmission system. Apart therefrom it may be desirable to control the different signals independently of one another. With the hitherto conventional circuit arrangements these requirements caused a relatively high expenditure of decoupling means.

When regarding e. g. the pilot frequency feeding in carrier wave signalling systems as being the present state of art, then it was hitherto the common practice to feed in the different signals via special decoupling devices arranged either in front or behind a final- or transmitting amplifier.

Fig. 1 as an example, shows one conventional arrangement of this kind. The signals S_1 and S_2 are admitted from different signal sources and each via a variable artificial extension line $V11$ and $V12$ and via a common decoupling network E to the transmitting amplifier V_s , whose gain can be controlled with the aid of a level controlled NR . Both of the amplified signals (v_1, S_1 ; v_2, S_2) can be controlled separately by means of the artificial extension lines $V11$ and $V12$.

Since the signal band to be transmitted is generally a very great one, very high demands have to be asked for from the decoupling means with respect to the frequency response characteristics of the impedances etc. Such decoupling networks arranged in the transmission path are the cause of an additional decoupling loss b_E , which has to be compensated again by correspondingly increasing the gain of the transmitting amplifier V_s , so that the level of the signal band S_1 exhibits its nominal value p_{S_1} at the output of the amplifier V_s .

The signal S_2 , fed-in via the decoupling network, is likewise supposed to have a predetermined level p_{S_2} at the output of the amplifier. In this respect there is often demanded an exactly defined and constant distance or space between the two level values.

The two variable artificial extension lines $V11$ and $V12$ are subject to the additional losses b_{V11} and b_{V12} , which likewise have to be compensated again in the transmitting amplifier.

The necessary increase of the gain in the transmitting amplifier V_s causes a deterioration of the non-linear attenuation and probably even an additional expenditure on tubes.

It is the object of this invention, irrespectively of this particular field of practical application, to provide a circuit arrangement enabling, without the employment of decoupling networks, the transmission of signals which are fed-in from different signal sources and which are reciprocally decoupled and capable of being separately controlled, to a common output circuit.

This will be achieved by providing an inverse feedback amplifier, to the input grid circuit of which there

2

are applied the signals originating with the one source, whereas the signals originating with the other source are fed into the negative feedback circuit.

The invention will now be described with reference to a particular example of embodiment by using the partially already discussed figures of the copending drawings.

Fig. 1 shows a block diagram relating to the state of art,

Fig. 2 shows a basic circuit diagram according to the present invention,

Fig. 3 explains the voltage amplification on principles,

Fig. 4 explains the current amplification on principles,

Fig. 5 serves to explain the regulating or control possibilities,

Fig. 6 shows a basic circuit diagram relating to the invention.

Fig. 2 on principle shows the arrangement of an exemplified embodiment according to the invention. The two signals originating with different sources are denoted by S_1 and S_2 . The signal S_1 with the voltage U_0 is applied to the terminals $a-b$ of an amplifier. To the terminals $c-d$ there is applied the signal S_2 with the current I_0 impressed by the input side. R_3 denotes the output load resistance lying between the terminals $e-f$. From these terminals $e-f$ there is tapped the output voltage and is applied to the negative feedback network GN which, e. g. consists of the resistances R_1 and R_2 . The amplification of S_1 is denoted by v_1 , and that of S_2 by v_2 .

In Fig. 3 there is explained the mode of operation of the arrangement for the amplification v_1 of the signal S_1 (voltage amplification).

U_0 denotes the original voltage

U_E denotes the input voltage of the amplifier V_s

U_K denotes the negative feedback voltage

U_3 denotes the output voltage across R_3

S denotes the effective transconductance of the amplifier V_s

$S \cdot U_E$ denotes the output current of the amplifier V_s at an input voltage U_E

According to Fig. 3

$$U_K = \frac{R_1}{R_1 + R_2} \cdot U_3 \quad (1)$$

and

$$U_3 = S \cdot (U_0 - U_K) \cdot \frac{R_3(R_1 + R_2)}{R_1 + R_2 + R_3} \quad (2)$$

when inserting (1) in (2), there will be

$$U_3 = S \cdot U_0 \cdot \frac{R_3(R_1 + R_2)}{R_1 + R_2 + R_3} - S \cdot \frac{R_3(R_1 + R_2)}{R_1 + R_2 + R_3} \cdot \frac{R_1}{R_1 + R_2 + R_3} \cdot \frac{R_1}{R_1 + R_2} \cdot U_3$$

The amplification v_1 of the signal S_1 —in the present case the signal $S_1 = U_0$ —will then become:

$$v_1 = \frac{U_3}{U_0} = \frac{S \cdot \frac{R_3(R_1 + R_2)}{R_1 + R_2 + R_3}}{1 + S \cdot \frac{R_3(R_1 + R_2)}{R_1 + R_2 + R_3}} =$$

$$\frac{R_1 + R_2}{R_1 + R_2 + R_3} + R_1 \quad \text{with } S \rightarrow \infty$$

$$v_1(S \rightarrow \infty) = \frac{U_3}{U_0(S \rightarrow \infty)} = \frac{R_1 + R_2}{R_1} = 1 + \frac{R_2}{R_1}$$

Hence it will be obvious that the amplification v_1 depends on R_1 and R_2 , and that this gain can be controlled with the aid of a variable R_1 and R_2 .

The amplification v_2 of the signal S_2 is explained with reference to Fig. 4.

- J_0 denotes the supplied current
 U_1 denotes the input voltage of the amplifier V_1 which becomes effective
 J_1 denotes the current across R_1
 J_2 denotes the current across R_2
 J_3 denotes the current across R_3
 S denotes the effective transconductance of V_1
 $S \cdot U_1$ denotes the output current of the amplifier V_1 in the case of the input voltage U_1 becoming effective.

According to Fig. 4

$$U_1 = J_1 \cdot R_1 \text{ and consequently } S \cdot U_1 = S \cdot (J_1 \cdot R_1)$$

There are established the following relationships

$$\begin{aligned} J_1 + J_2 + J_3 &= J_0 \\ J_1 (S \cdot R_1) - J_2 - J_3 &= 0 \\ -J_1 R_1 + J_2 R_2 - J_3 R_3 &= 0 \end{aligned}$$

When solving the equations according to J_3 and by converting, there will be obtained

$$-J_3 [(1 - S \cdot R_2) R_1 + (1 + S \cdot R_1) (R_2 + R_3)] = J_0 \cdot (1 - S \cdot R_2) \cdot R_1$$

and therefrom the amplification v_2 of the signal S_2

$$v_2 = \frac{J_3}{J_0} = \frac{-R_1 + S \cdot R_1 \cdot R_3}{R_1 + R_2 + R_3 + S \cdot R_1 \cdot R_3} = \frac{-\frac{R_1}{S} + R_1 \cdot R_2}{R_1 + R_2 + R_3 + R_1 \cdot R_3}$$

and finally

$$v_2 = \frac{J_3}{J_0 (S \rightarrow \infty)} = \frac{R_2}{R_3}$$

Accordingly, the amplification v_2 of the signal S_2 is independent of R_1 in the limiting case ($S \rightarrow \infty$) and is capable of being controlled with the aid of R_2 .

Fig. 5 on principle shows how the selective control of the amplification of v_1 and v_2 is practically carried out. The corresponding designations are the same as in the preceding figures.

- v_1 denotes the amplification of the signal S_1
 v_2 denotes the amplification of the signal S_2

$$\begin{aligned} \alpha_1 &= f_1(\alpha) \\ \alpha_2 &= f_2(\alpha) \end{aligned}$$

denotes the given functional dependence of the variable resistances R_1 and R_2 .

With a bridge arranged at A

$$v_1 = 1 + \frac{R_2}{\alpha_1 R_1}$$

becomes variable with α_1 and

$$v_2 = \frac{R_2}{R_3} = \text{constant}$$

With a bridge arranged at B

$$v_1 = 1 + \frac{\alpha_2 R_2}{R_1}$$

becomes variable with α_2

$$v_2 = \frac{\alpha_2 R_2}{R_3}$$

becomes variable with α_2 .

With bridges arranged at A and B

$$v_1 = 1 + \frac{\alpha_1 R_2}{\alpha_2 R_1} = 1 + \frac{\alpha_1}{\alpha_2} \cdot \frac{R_2}{R_1}$$

becomes variable with α_1 and α_2

$$v_2 = \frac{\alpha_2 R_2}{R_3}$$

becomes variable or controllable with α_2 for

$$\alpha_1 = k_1 \cdot \alpha_2 \text{, there becomes } v_1 v_2 = 1 + \frac{k_1}{k_2} \cdot \frac{R_2}{R_1} = \text{constant}$$

Hence it can be recognized that

(1) At an inserted bridge A the amplification v_1 of the

signal S_1 can be controlled, whilst the amplification v_2 of the signal S_2 remains constant;

(2) At an inserted bridge B the amplifications for both signals can be controlled proportionally, and that

(3) In the case of inserted bridges A and B the amplification v_1 will now remain constant, whilst the amplification v_2 is capable of being controlled.

In Fig. 6 of the copending drawings there is shown a basic circuit diagram for a three-tube amplifier which is built up according to the present invention. The designations are the same as those used in the preceding figures. The signal S_1 with the voltage U_0 is applied via an input transformer to the amplifier, whilst the signal S_2 with the current I_0 is fed into the negative feedback circuit.

15 The control is effected at R_1 by means of bridge A for v_1 , thereby v_2 will remain constant. With the aid of a bridge B at R_4 , v_1 and v_2 will be controlled in common. With both of the bridges it will be possible e. g. to control v_2 with $v_1 = \text{constant}$. With the aid of the bridges it is possible to control the signals either independently of each other or in common.

20 The present state of art and the therefrom resulting setting of the problem was taken from the fields of carrier frequency technique. From this there also results e. g. a particular applicability of the present invention to the pilot frequency feed-in in carrier wave signalling systems.

25 The invention has been described hereinbefore with reference to an example of embodiment. This, however, in no way represents a limitation to the scope of the invention and its range of practical application.

30 While I have described above the principles of my invention in connection with specific apparatus, it is to be clearly understood that this description is made only by way of example and not as a limitation to the scope of my invention as set forth in the objects thereof and in the accompanying claims.

35 What is claimed is:

40 1. An amplifying circuit for the transmission of two signals simultaneously without intermodulation comprising two sources of respectively different signals of similar amplitude, a common linear amplifier therefor connected to each source, said amplifier having a negative feedback path to which one of said sources is connected and a forward amplifying path to which the other source is connected, means in said feedback path for separately controlling the amplification of each of said signals, and a common load for said signals connected to said amplifier.

45 2. The amplifying circuit of claim 1, wherein the means in said feedback path are variable, linear passive impedances for controlling the amplification of each of said signals selectively.

50 3. The amplifying circuit of claim 2, wherein said amplifier comprises three electron tubes coupled together, said tubes each having cathode, grid and anode electrodes, and said impedances being connected to the cathodes of the first and third tubes respectively.

55 4. The amplifying circuit of claim 3, and an output circuit connected to the third tube comprising a transformer having three windings, said load being connected to one winding and said impedances to another.
